UNITED STATES PATENT OFFICE.

HENRY A. HOUSE, OF BRIDGEPORT, CONNECTICUT.

PAPER BAG.

SPECIFICATION forming part of Letters Patent No. 247,646, dated September 27, 1881.

Application filed September 21, 1880. (No model.)

To all whom it may concern:

Be it known that I, HENRY A. HOUSE, of Bridgeport, Fairfield county, Connecticut, have invented certain new and useful Improvements 5 in Paper Bags, of which the following is a specification.

The object of my invention is a paper bag constructed as fully described hereinafter, so as to prevent mistakes and loss of bags, time, 10 and material in packing.

In retail stores, where paper bags are used to receive and pack the various articles sold to customers, there is a large percentage of loss resulting from mistakes by salesmen in selecting bags of improper size and in changing the 15 contents from one bag to another. Thus, where the salesman having mistaken the capacity of a bag finds that it will not hold the quantity measured, he must return the contents to the 20 scoop or tray and secure another bag of proper dimensions, with some loss of time, and generally with the loss of the bag and of material; or, if he selects a bag which is larger than necessary, there is a corresponding waste. Al- 25 though the loss of time or bags or material is slight in each case, the aggregate is so large as to be of considerable importance, and to induce tradesmen to resort to various expedients, as assorting the bags in indexed trays, &c., none of which have proved effective, while 30 all are more or less complicated or expensive.

I have secured the desired result by manufacturing a bag with a scale or index forming

part of the same, and indicating in any suitable manner not only the actual capacity of the 35 bag, but the amounts of different material which it is capable of holding. This may be effected in various ways. I prefer, however, to stamp or emboss the bag as it passes through the machine, thereby marking it without any 40 increase of cost, and to designate the capacity of the bag by words and figures, substantially as shown in the accompanying drawing, the names of the articles varying, of course, with the character of materials on sale. 45

I am aware that it has been common to print upon a bag a figure indicating its number or size, but such mark is of no value in determining its capacity, inasmuch as a bag capable of holding one pound of black tea will not hold 50 one pound of green tea, nor will one of a capacity to receive one pound of pepper hold one pound of coffee.

I claim—

As a new article of manufacture, a paper bag 55 provided with marks or characters indicating the capacity of said bag for a series of different materials, as set forth.

In testimony whereof I have signed my name to this specification in the presence of two sub- 60 scribing witnesses.

HENRY A. HOUSE.
